UNITED STATES PATENT OFFICE.

JOHN A. LYONS AND EDWARD C. BROADWELL, OF CHICAGO, ILLINOIS.

PROCESS OF PRODUCING AMMONIA.

No. 816,928.

Specification of Letters Patent.

Patented April 3, 1906.

Application filed September 2, 1904. Serial No. 223,158.

To all whom it may concern:

Be it known that we, JOHN A. LYONS and EDWARD C. BROADWELL, citizens of the United States, residing at Chicago, in the county of Cook and State of Illinois, have invented new and useful Improvements in Processes of Producing Ammonia, of which the following is a specification.

Our invention relates to a process of producing synthetic ammonia from the borates of the electropositive metals in conjunction with nitrogen.

The means employed in carrying out our invention are illustrated in the accompanying drawing, which is a vertical sectional view of an apparatus the parts of which are designated by suitable reference-letters. Our invention, however, does not rest upon the use of any one form of apparatus.

In this apparatus as here shown A is a crucible.

B is a fire or other suitable means of external heat; C, an internal positive electrode or anode of carbon, the negative electrode or cathode being formed by the crucible A.

D is a pipe or annular jacket surrounding the anode and made of some suitable resistive material, preferably graphite. This pipe or annulus also serves as a partition between the anode or cathode. The course of the current is represented by the arrows E.

In carrying out our invention the borates of any of the electropositive metals—such as potassium, sodium, manganese, chromium, molybdenum, tungsten, uranium, and vanadium, or a mixture of the borates of these metals—are maintained in a state of fusion in the crucible. This fused state may be maintained either by the fire B or it may be maintained by causing a sufficient amount of the electric energy of the current to fall as Joule heat. Through this fused bath is passed an electric current, whereby not only electrolysis of the borates is effected, but also an intense heat created at the carbon anode by the relatively high resistance in the bath at or near the anode, owing to the fact that the anode, as shown, has a surface of much smaller area than the inner surface of the retaining-crucible, which acts as the cathode. At the same time nitrogen-bearing gases or pure

nitrogen gas itself is passed into the bath down through the annulus or pipe of resistive material surrounding the anode. The nitrogen is introduced by means of a vessel F, having a stem depending into the annulus D. The electrolysis produces anion, boric anhydrid, and oxygen at the anode, where the intensely-heated carbon acts as a reducing agent to chemically reduce the anion to boron. The pipe serves to prevent the boron thus formed from floating over to the cathode and the nitrogen introduced into the pipe combines with the boron to form boron nitrid. The metal of the borates will be deposited at the cathode. Then after sufficient boron nitrid has accumulated it is subjected while separated from the metals to steam at a temperature of 600° centigrade or above. This may be done either by withdrawing the boron nitrid from the bath or else after the deposited metal has been withdrawn therefrom passing steam at the same temperature into the bath, in either case causing the boron to revert the boric anhydrid (B_2O_3) and producing synthetic or artificial ammonia by the following reaction:

The temperature of the bath is maintained at about 1,000° centigrade.

Having thus described our invention, what we claim is—

1. The process of subjecting a fused bath of the borates of electropositive metals to electrolytic action and subjecting the anion produced thereby to a reducing agent at the anode in the presence of an intense heat and introducing nitrogen into said bath at the anode and then subjecting the boron nitrid thus produced to steam.

2. The process of producing boron from the borate of an electropositive metal by electrolysis and a reducing agent of intense heat at the anode, introducing nitrogen at the anode, and subjecting the boron nitrid while separated from the deposited metal to the action of steam at 600° centigrade or above.

3. The process of subjecting a fused bath of the borate of an electropositive metal to electrolysis and chemically reducing the

boric anhydrid to boron at the anode, in the presence of an anode separated from the cathode by a jacket of resistive material introducing nitrogen between said anode and 5 jacket and subjecting the boron nitrid thus produced to the action of steam at a sufficient temperature to cause the boron to revert to boric anhydrid.

In testimony whereof we have hereunto affixed our signatures.

JOHN A. LYONS.
EDWARD C. BROADWELL.
